UNITED STATES PATENT OFFICE.

HAROLD J. GERPHEIDE, OF SOUTH BEND, INDIANA.

TIMER FOR GAS-ENGINES.

1,269,806.

Specification of Letters Patent. Patented June 18, 1918.

Application filed July 11, 1917. Serial No. 179,981.

To all whom it may concern:

Be it known that I, HAROLD J. GERPHEIDE, a citizen of the United States, residing at South Bend, in the county of St. Joseph and

5 State of Indiana, have invented certain new and useful Improvements in Timers for Gas-Engines, of which the following is a specification.

This invention relates generally to an improvement in timers of that type, as used particularly on Ford automobiles, wherein the wire leads to the fixed contacts are arranged exteriorly of the timer and wholly free of protection. With such a type of 10 timer the wires are exposed to the accumulation of dirt, oil, or the like, which tends to destroy their insulation, and frequently results in imperfect timing action.

The main object of the present invention 20 therefore is the construction of a timer in which the wires are or may be completely housed, while at the same time, through the removal of a closure adapted for removal, such wires or their connections to the fixed 25 contacts of the timer, are readily accessible for any and all purposes.

The wire housing of the timer includes an annular channel into which the fixed contact posts project, and in which the wires 30 leading from such posts are housed, the channel having a removable cover plate, and the timer casing having an integral wire-receiving channel leading to the center of the casing from the housing, all of the 35 wires passing through said channel. A coupling, through which the wires pass beyond the casing has a rotary bearing or slip-joint connection with the casing, and beyond the casing is connected to an ordinary type 40 of wire conduit. The holding spring ordinarily employed for securing the timer casing in place bears upon the coupling, so that the casing when moved, as in advancing or 45 retarding the spark, rotates in effect on the coupling and engine base wall, preventing undue movement of the wires under such adjustment of the casing.

The invention in the preferred form is 50 illustrated in the accompanying drawings, in which:

Figure 1 is a view in elevation showing the improved timer construction.

Fig. 2 is a section on line 2—2 of Fig. 1.

The present invention is, as previously 55 stated, directed to improving the timer usually employed in Ford automobile igni-

tion parts, so that the wires forming part of such timing structure, may be fully and completely protected.

The usual timer casing 1 is of conical 60 formation, having an annular base wall 2 in which, through proper insulating units 3 are mounted the fixed contacts 4, adapted to be successively engaged by the rotor contact 5, mounted on and operated by the 65 timing shaft 6. The free or inner edge of the wall 2 is mounted in a circular recess 7 in the engine base wall 8, a rotary bearing being thus provided for the casing to permit its necessary movement in advancing 70 or retarding the spark, as through the dash-operated connection 9.

The fixed contacts 4 extend beyond the wall 2 in the form of binding posts 10, and the respective wires 11 are adapted for connection to these posts. As heretofore constructed the wires are entirely free beyond the casing, so far as any protective means is concerned, with the result that these wires are comparatively short lived, electrically 80 speaking, as they are exposed to all accumulations and contact wear.

The present invention contemplates the complete housing of these wires, and to this end the casing 1 is provided with a wire 85 housing arranged about the wall 2 of such casing. The housing comprises spaced parallel walls 12 and 13 projecting at right angles to and outwardly from the casing wall 2. The inner surfaces of the free edges 90 of the walls 12 and 13 are recessed at 14 to receive a cover plate 15, preferably in the form of a split ring having out-turned ears 16 at the meeting ends, to be engaged by a securing means, such as a nut and bolt 17. 95

An annular housing is thus formed about the casing, in which housing the binding post ends of the fixed contacts 4 are located, together with the wires leading from said binding posts. The housing is closed on its 100 outer side by a cover plate which may be readily removed at will, and when removed, fully and completely exposes all connections within the housing, so that the parts may be readily reached for adjustment or repair. 105

The conical wall of the casing is provided with a hollow enlargement, extending radially thereof, as at 18, this enlargement opening at one end into the housing described, and at the opposite end into an annular bearing section 19, forming the apex of the casing. The annular section 19 is 110

channeled or recessed on its inner surface to provide a bearing 20. A coupling 21 has one end formed to fit into the bearing recess 20 and provide a slip-joint connection therewith, the opposite end of the coupling being formed to removably receive and secure the end of an ordinary flexible wire conduit 22. The wires from the respective fixed contacts extend through the housing to and 10 through the channel 18, through the coupling 21 and conduit 22, being protected at all times from dirt accumulations, from wearing contacts, to thus materially increase the length of use of such wire connections.

The casing as an entirety is, as stated, movable to advance or retard the spark, and to provide for the complete separation of the casing from the engine wall when desired, a spring strip 23 has been heretofore employed. This strip, heretofore secured to the engine wall and movably bearing on the apex of the casing, is to be used in the present structure, though in this instance 20 the bearing end of the spring engages the coupling 21, in line with the apex of the casing. This permits axial movement of the casing, without permitting movement of the coupling, the slip-joint connection between 25 the coupling and casing taking care of such relative movement. All parts are readily removable by displacing one end of the spring plate 23, the bearing end of such plate being preferably formed with a projection 24 to seat in a depression 25 in the coupling 21.

What is claimed as new is:

1. A timer casing having fixed contacts projecting through one wall thereof, a hous-

ing integral with the casing and inclosing 40 the projecting portions of said contacts, an enlargement on the casing forming a channel in communication with the housing, and a conduit coupling in communication with the channel and having a slip-joint connection with and axially of the casing, whereby the casing may have rotative movement without moving the coupling.

2. A timer casing having fixed contacts projecting through one wall thereof, a housing integral with the casing and inclosing 50 the projecting portions of said contacts, an enlargement on the casing forming a channel in communication with the housing, a conduit coupling in communication with the channel and having a slip-joint connection 55 with and axially of the casing, to permit the latter to have rotative movement without moving the coupling, and means bearing upon the coupling to secure the parts in 60 relative positions.

3. A timer casing mounted for rotary adjustment and having fixed contacts projecting through one wall thereof, spaced annular walls projecting at right angles to the 65 axis of the casing and to the first-mentioned wall thereof, a removable cover plate engaging the free edges of the said annular walls, to provide an inclosed housing about said contacts, a conduit coupling having a 70 slip-joint connection with and axially of the casing to permit the latter to have rotative movement without moving the coupling, and a conduit secured to the coupling and fixed against movement.

In testimony whereof I affix my signature.

HAROLD J. GERPHEIDE.
